Application October 7, 1954, Serial No. 32,568

Term of patent 14 years

(Cl. D80—10)

To all whom it may concern:

Be it known that I, Morris Lubow, citizen of the United States, residing at Brooklyn, in the county of Kings and State of New York, have invented a new, original, and ornamental Design for an X-Ray Apron and Glove Support, of which the following is a specification, reference being had to the accompanying drawing, forming part thereof.

In the drawing the figure is a perspective view of an X-ray apron and glove support showing my new design.

The dominant features of my design reside in the portion shown in full lines.

I claim:

The ornamental design for an X-ray apron and glove support, substantially as shown and described.
